US00D747879S

(12) **United States Design Patent**
Fair et al.

(10) **Patent No.:** US D747,879 S
(45) **Date of Patent:** ** Jan. 26, 2016

(54) **CORD GRIPPING HANDLE**

(71) Applicant: **Thule Organization Solutions, Inc.**,
Niwot, CO (US)

(72) Inventors: **Paul Fair**, Denver, CO (US); **Jamie Kummerfeld**, Greeley, CO (US)

(73) Assignee: **Thule Organization Solutions, Inc.**,
Niwot, CO (US)

(**) Term: **14 Years**

(21) Appl. No.: **29/495,275**

(22) Filed: **Jun. 30, 2014**
